UNITED STATES PATENT OFFICE.

JOHN DRAPER, OF WHITBY, ONTARIO, CANADA.

CHILD'S SLATE-CLEANER AND PENCIL HOLDER AND SHARPENER.

SPECIFICATION forming part of Letters Patent No. 402,814, dated May 7, 1889.

Application filed February 23, 1889. Serial No. 300,891. (No model.)

To all whom it may concern:

Be it known that I, JOHN DRAPER, of the town of Whitby, in the county of Ontario, in the Province of Ontario, Canada, gentleman, 5 have invented a certain new and useful Combined Child's Slate-Cleaner and Pencil Holder and Sharpener, of which the following is a specification.

The object of the invention is to design a 10 combined child's slate-cleaner and pencil holder and sharpener; and it consists, essentially, of a neat water-bottle provided with wings designed to hold two pieces of sponge, between which wings a holder to receive and 15 retain the pencil is formed, the mouth of the bottle having a small opening closed by a spring-cap readily opened by pressure, so that the water in the bottle may easily be sprayed upon the slate or retained in the bottle by the 20 action of the said spring-cap, a V-shaped cutter being fixed on the back of the bottle, the whole being arranged substantially as and for the purpose specified.

Figure 1 shows my combined child's slate-cleaner and pencil holder and sharpener as it 25 will appear when being used for spraying water on a slate. Fig. 2 shows it as it will appear when being used for rubbing a slate. Fig. 3 shows it as it will appear when a pencil is being sharpened on it.

A represents the water-bottle, which may be made of metal, glass, or any other suitable material.

B represents the plug for closing the mouth 35 of the bottle A, which plug may be readily removed when it is desired to fill the said bottle with water. This plug has a small opening through it, the mouth of which opening is closed by a spring-cap, C, which is designed so 40 that it will, when in its normal position, press against and close the said opening.

When it is desired to sprinkle the water onto the slate, the spring-cap C is pressed upon

by the finger, as indicated in Fig. 1, when the water will be permitted to spray out, as indicated. 45

Two wings, D, are fixed to the bottle A and designed to hold the sponges E and F, the sponge E being designed to rub the wet slate and the sponge F to dry it. Of course there 50 is no difference between the sponges, except that one is used for one purpose and the other for another purpose.

It will be noticed that a holder, G, is fixed to the bottle A between the wings D. This 55 holder is designed to hold the pencil H. A plate, I, is fixed to the bottle A and has a V-shaped notch cut in it, as indicated. In order to sharpen the pencil H, it is merely necessary to place its end between the plate I and the 60 bottle A, so that the said end of the pencil shall fit into the notch formed in the said plate, when, by causing the pencil to revolve, its end will be beautifully sharpened by the action of the edges of the notch cut in the 65 said plate.

What I claim as my invention is—

1. A slate-cleaner consisting of a bottle, A, provided with a plug, B, having a small opening in it protected by the spring-cap C, and 70 one or more wings, D, designed to hold a sponge, substantially as and for the purpose specified.

2. A slate-cleaner and pencil-sharpener consisting of a bottle, A, provided with a plug, B, having a small opening in it protected by the 75 spring-cap C, one or more wings, D, designed to hold sponges, the pencil - holder G, and sharpening-plate I, attached to the bottle, substantially as and for the purpose specified.

Whitby, February 12, 1889.

JOHN DRAPER.

In presence of—

JAMES DRAPER,
SARAH DRAPER.
